UNITED STATES PATENT OFFICE.

JEROME R. GEORGE, OF WORCESTER, AND ELBERT H. CARROLL, OF WEST BOYLSTON, MASSACHUSETTS, ASSIGNORS TO MORGAN CONSTRUCTION COMPANY, OF WORCESTER, MASSACHUSETTS, A CORPORATION OF MASSACHUSETTS.

DIE BOX FOR WIREDRAWING MACHINERY.

Application filed February 13, 1922. Serial No. 536,394.

To all whom it may concern:

Be it known that we, JEROME R. GEORGE and ELBERT H. CARROLL, both citizens of the United States, residing, respectively, at 5 Worcester and West Boylston, in the county of Worcester and Commonwealth of Massachusetts, have invented a new and useful Improvement in a Die Box for Wire-drawing Machinery, of which the following, 10 together with the accompanying drawings, is a specification.

The present invention relates to the boxes that are used for holding the dies employed in the drawing of wire. And more particularly, the invention contemplates the provision of a box having improved means for retaining the die securely and rigidly in position therein, said retaining means being instantly adaptable to dies of various 20 sizes, without affecting the rigidity with which the die member is held.

The several features and advantages of our improved construction are set forth in detail in the following description, reference being had to the accompanying drawings, wherein—

Fig. 1 is a view in side elevation of our improved die box.

Fig. 2 is an end elevation of same.

Fig. 3 is a top plan view of same.

Fig. 4 is a view similar to Fig. 1 showing the use of a different sized die.

Like reference characters refer to like parts in the different figures.

The invention is here shown as applied to a die box of conventional form, the same comprising side walls 1, 1, a bottom 2, a front wall 3 and a rear wall 4, whereby to inclose a suitable chamber for the retention 40 of powdered soap or other lubricant. According to the usual practice, the side walls 1, 1 provide a transverse opening 5 for the insertion and removal of the die, the latter being adapted to bear against the front wall 3 with its hole in registry with an opening 6 in said wall for the passage of the wire.

The usual method of disposing the die in proper position involves the employment 50 of supporting blocks or wedges of the required thickness to obtain the correct height of the die opening; in die boxes of ordinary construction, a screw is employed, acting directly against the upper face of the die

to exert a downward pressure thereon, 55 whereby to retain it in position. This method of retention is unsatisfactory; first, because the contact surface between die and screw is very limited, owing to the bevel of the die surface; second, because the retaining force is exerted only in a perpendicular direction and hence does not insure any pressure against the front wall 3 of the box; third, because the tightening of the screw, whose end is directly in contact with the 60 surface of the die, has a tendency to displace the die laterally; and finally, because the die, usually trapezoidal in section, tends to tip on its lower edge when the perpendicular pressure of the screw is applied. 65

The present invention overcomes the foregoing disadvantages by a construction which causes the retaining force to be exerted obliquely, against the rear upper edge of the die, so that simultaneously with the 70 downward pressure on the die there is exerted a pressure to force the die against the front wall 3 of the box. As shown most clearly in Fig. 1, the small sized die 7, of the usual construction, is supported on a 75 block 8. For the purpose of holding this die in place, the die box at its front end provides a rearwardly directed flapper 9, which is pivoted on a pin 10 extending transversely across the space between the 80 walls 1, 1. The lower surface of flapper 9 bears against the rear upper edge of the die, and said flapper on its upper surface is subjected to the pressure of the usual retaining screw 11, which is threaded into 85 a hole 12 provided by a portion 13 of the box which extends across the top thereof at the front end. To facilitate the entrance of a die from the side of the box, the flapper 9 is yieldingly maintained in a withdrawn position by means of a spring 14 bearing against an arm 15 thereof. 90

As shown in Fig. 4, the construction described is adaptable to the retention of a much larger die 16, said die being seated 100 on a suitable block or wedge 17. As before, the flapper 9 bears against the rear upper edge of this die, and thus said flapper affords an extended contact surface to receive the pressure of the screw 11, which pressure is exerted obliquely to force the die against the front wall 3 of the box as well as against the block or wedge 17. The turn- 105

ing movement of the screw 11 to tighten the grip on the die takes place without any danger of displacing the die laterally, since the end of the screw bears not against the die, but against the flapper 9 which cannot shift laterally, but can only swing about its pivot 10.

We claim:

1. The combination with a box or holder for a die, of means for retaining the die therein by pressure exerted obliquely downward, whereby to crowd said die against the front wall of said box.
2. The combination with a box or holder for a die, of means carried thereby and engageable with the rear upper edge of the die, to exert a retaining pressure on said die obliquely.
3. The combination with a box or holder for a die, of pivoted means carried by said box and adapted to engage the rear upper

edge of a die therein, and means for exerting downward pressure on said pivoted means, to retain said die in place.

4. The combination with a box or holder for a die, of a member extending rearwardly from the front of said box for engagement with the rear upper edge of a die, and a screw for exerting downward pressure on said member.

5. The combination with a box or holder for a die, of a member extending rearwardly from the front of said box for engagement with the rear upper edge of a die, said member being pivoted, whereby to adjust itself to different sizes of dies, and means for exerting downward pressure on said member, to retain the die in place.

Dated this 10th day of February, 1922.

JEROME R. GEORGE.
ELBERT H. CARROLL.
